(57) **CLAIM**

The ornamental design for a fryer and roaster, as shown and described.

DESCRIPTION

FIG. 1 is a top plan view of the present fryer and roaster;

FIG. 2 is a front elevational view thereof;

FIG. 3 is a rear elevational view thereof;

FIG. 4 is a side elevational view thereof, the opposite side being a mirror image;

FIG. 5 is an isometric view of the present fryer and roaster shown on a closed position; and,

FIG. 6 is an isometric view of the present fryer and roaster shown in an opened position.

The broken lines shown in the drawings are for illustrative purposes only and form no part of the claimed design.
